BREAST PROTECTOR

Thelma L. Cox, West Los Angeles, Calif.

Application July 11, 1934, Serial No. 734,672

1 Claim. (Cl. 128—280)

The present invention relates to improvements in apparel and has reference more particularly to a breast protector which is especially designed for nursing mothers.

5 The primary object of the present invention resides in the provision of a breast protector that will positively prevent any milk from coming in contact with the clothing and soiling the same, and without causing any discomfort to the 10 wearer.

A further and important object is to provide a breast protector of the above mentioned character that includes means for readily and easily securing the device in position to receive and 15 enclose the breasts, the supporting means being adapted to be detachably connected to the shoulder straps of the brassiere or slip, under which the breast protector is worn.

A further object is to provide a breast protector of the above character which is simple in construction, inexpensive to manufacture, durable and further well adapted for the purposes for which it is designed.

Other objects and advantages of the present 25 invention will become apparent from the following description when taken in connection with the accompanying drawing.

In the drawing, wherein like reference characters designate corresponding parts throughout 30 the several views:

Figure 1 shows my improved breast protector as it appears when being worn beneath a slip;

Figure 2 is a side elevation disclosing a portion of the slip broken away to more clearly 35 disclose the manner in which the breast protector is used;

Figure 3 is a rear face view of my improved breast protector; and

Figure 4 is a vertical sectional view taken 40 approximately on the line 4—4 of Figure 3, through one of the pockets.

In the drawing, wherein for the purpose of illustration is shown the preferred embodiment of my invention, the numeral 1 designates generally 45 my improved breast protector, the same comprising a pair of identical pockets formed preferably of rubberized material.

Each pocket is formed of two pieces of material and comprises a front section 2 that is 50 substantially elliptical in shape, and a rear section or part 3 that is substantially half-moon shaped, as clearly illustrated in Figure 3. The front and rear section of each pocket are vulcanized together along their lower edges to as- 55 sure against any leakage of the milk that may

collect in the pocket when the breast protector is in use. A binding tape 4 extends over the vulcanized lower edges of the sections of each pocket and is stitched thereto.

A similar binding tape 5 is stitched to the upper edge of the front section 2 and this binding tape 5 is of such length as to extend across both pockets thereby connecting the two pockets in juxtaposed relation with each other. 5

As clearly disclosed in Figure 2, the breasts 10 are confined within their respective pockets with the rear section 3 being disposed underneath while the front section extends completely over the top face of the breasts.

My improved breast protector further includes 15 a novel means for supporting the same in position on the body of the wearer and to this end, there is provided a pair of relatively short straps or tabs 6, one tab being connected to the upper edge portion of the front section of each pocket 20 at the center thereof by stitching. A snap fastener of the conventional construction is associated with the respective ends of each tab, the male or head portion of such separable fastener being designated by the numeral 7 and 25 being connected to the end of the tab that is stitched to the front section of each pocket while the female or socket portion of the snap fastener that is designated by the numeral 8 30 is carried by the free end of each tab. 30

The tabs 6 are adapted to be disposed around the shoulder strap 9 of the slip 10, under which the breast protector is worn and after being passed around these shoulder straps, the socket members 8 are connected to the heads 7 thereby 35 positively connecting the breast protector to the shoulder strap and by which the device is properly supported in position.

While I have shown the breast protector as 40 being worn beneath a slip, it is to be understood that the same may also be worn beneath a brassiere or the like and I do not wish to limit myself to the particular undergarment with which my breast protector may be associated.

In supporting the breast protector from the 45 shoulder straps of an undergarment in the particular manner disclosed and illustrated in the drawing, the use of back encircling supporting straps and safety pins is entirely eliminated, thus enabling the device to be readily and easily 50 attached in position and removed when necessary and when worn, the device will cause no discomfort whatsoever to the wearer.

The advantages of this device are readily 55 apparent and much of the inconvenience and

annoyance to nursing mothers is wholly avoided.

While I have shown the preferred embodiment of the invention, it is to be understood that minor changes in the size, shape and arrangement of parts may be resorted to without departing from the spirit of the invention and the scope of the appended claim.

Having thus described the invention, what is claimed is:

- 10 In a breast protector of the class described, a pair of breast receiving pockets, each pocket being formed of rubberized material and including an elliptically shaped front section, and a half-moon shaped rear section, said sections be-

ing vulcanized together along their lower edges, a binding tape extending over the vulcanized lower edges of said sections of each pocket, an additional binding tape extending across the upper edges of the front sections of the two pockets to connect the same together in juxtaposed relation with each other, shoulder strap encircling tabs attached to the upper edges of the front sections of the respective pockets to support the breast protector on the body of the wearer in position to receive the breasts, and a separable fastener associated with each tab for holding the same in loop forming relation.

THELMA L. COX.
